TRIMMING MACHINE

George Goddu, Winchester, Mass., assignor to
 United Shoe Machinery Corporation, Paterson,
 N. J., a Corporation of New Jersey

Application January 24, 1931. Serial No. 510,915

2 Claims. (Cl. 12—82)

This invention relates to trimming machines and is herein illustrated as embodied in a machine constructed and arranged to sever surplus material projecting from the bottom face of the 5 insole of a lasted shoe. A novel feature of the invention is concerned with means arranged to regulate the closeness of trimming while the trimming operation is in progress.

An example of work involving a typical problem 10 for which a machine embodying the present invention is especially suited is illustrated and described in my copending application Serial No. 386,097, filed August 15, 1929. As illustrated in that case, the insole of the shoe is provided with 15 upstanding lips extending along the opposite margins thereof from the forward part of the heel seat nearly to the toe end, where they meet, the lips being set in from the edges of the insole a distance of about one-half inch. In lasting 20 such a shoe according to the method described in said copending application, the overdrawn portion of the upper is stuck to the margin of the insole by an adhesive, but in addition, fasteners, preferably slender staples, are inserted 25 through the margin of the upper and through the lips of the insole to maintain the tightly lasted condition of the upper while the adhesive is setting. To this end the upper is cut to provide 30 a marginal surplus which stands up from the bottom of the insole and lies against the outer faces of the aforesaid lips. The fasteners are inserted as closely as possible to the roots or bases of the upstanding lips of the insole. Subsequently, the upstanding lips of the insole and the corresponding 35 upstanding margin of the lasted upper may be trimmed flush with the bottom of the shoe in the forepart to provide a smooth, even surface for receiving an adhesively-secured outsole, the upstanding lips and the corresponding margin of 40 the upper in the shank portion of the shoe being trimmed less closely, that is, above the level of the fasteners, whereby these fasteners are retained in the shank portion of the finished shoe to supplement the adhesive by which the upper 45 and the insole are connected. The shallow channel between the unsevered portions of the lips in the shank portion is adapted to receive a shank-stiffener.

In view of the foregoing, an object of the present invention is to provide an improved machine 50 adapted to sever surplus material standing up from the bottom of a lasted shoe, whereby, at the will of the operator, and even while the machine is operating, the line of severance may be shifted 55 to and from the plane of the exposed bottom face

of the insole, to the end that the trimming may be substantially flush with that face wherever such trimming is desired without necessarily being flush at other localities.

In accordance with the object above set forth 60 and with a feature of the invention, the illustrated trimming machine comprises a trimming gage the work-engaging portion of which is formed and arranged to bear in a channel in the bottom surface of the insole of a lasted shoe, cutting means arranged to sever a lip or flange of material projecting from the channel with a cut that may be flush with the bottom surface of the 65 insole, and manually operative means by which the trimming gage and the cutting means may be 70 relatively shifted while in operation to alter the closeness of the trimming cut.

As herein illustrated, the movable trimming gage is arranged to engage the work at a point in advance of the point where the trimming 75 means operates and is so formed that it can be retracted as far as may be necessary to permit severing the upstanding materials flush with the bottom surface of the shoe.

Referring to the accompanying drawings, 80 Fig. 1 is a right-hand elevation of a trimming machine embodying the present invention in a preferred form;

Fig. 2 is a perspective rear view of a lasted shoe 85 in process of being trimmed in accordance with the requirements hereinbefore mentioned, the figure including portions of the trimming means and the movable gage by which the closeness of trimming is regulated;

Fig. 3 is a sectional view on a larger scale of a 90 portion of the forepart of a lasted shoe, the surplus material of which has been trimmed flush with the plane of the shoe bottom; and

Fig. 4 is a cross-sectional view of the shank 95 portion of a lasted shoe, the surplus material of which has been trimmed above the level of the staples by which the upper is secured to the lip or rib of the insole.

The shoe illustrated in Fig. 2 is lasted in accordance with the method described in the above-mentioned copending application Serial No. 386,097. It comprises a leather insole 10 having a marginal feather 12 and upstanding lips each composed of two flaps 14 and 16 split from the insole and bent upwardly from a common root 105 18. The lips of the insole extend along opposite margins thereof from the forward portion of the heel seat to a point near the toe where they meet at an acute angle.

The upper, consisting of an outer layer 20 of 110

leather or other material and a lining 22, is drawn tightly against a last 24 and is secured to the insole at the heel-seat portion by heel-seat tacks 26, but throughout the forepart and 5 along opposite sides of the shank it is secured to the feather 12 and to the upstanding lips of the insole by an adhesive. Slender wire staples 28, inserted at intervals through the upstanding marginal portion of the upper and through the 10 upstanding lips of the insole along the shank portion and in the ball portion of the shoe, are used to maintain the lasting tension of the upper while the adhesive is setting. Detachable holding means, which need not be described for the 15 purpose of explaining the present invention, are used to maintain the lasting tension of the upper in the forepart and at the toe of the shoe while the adhesive is setting but are subsequently removed, with the result that at these localities the 20 connection between the upper and the insole of the finished shoe will be maintained solely by the adhesive with which the contacting faces of the upper and the insole have been coated prior to the lasting operation.

25 The stock split from the feather 12 of the insole to provide the upstanding flap 14 is replaced by the overdrawn material of the upper, with the result that the bottom surface 30 of that portion of the upper which lies on the 30 feather 12 (see Fig. 3) lies substantially in the plane of the exposed bottom surface 32 of the insole. The upper is cut to provide surplus marginal material by which it may be gripped for lasting purposes and also to provide an upstanding 35 flange 33 to receive the lasting staples 28. These staples are located slightly above the bend or angle 34 (see Fig. 4) of the upper material which is tucked snugly into the angle formed by the feather 12 and the lip of the insole.

40 A shoe of the type herein described is subsequently provided with an outsole which is secured thereto by an adhesive only, except at the heel seat where heel-attaching nails may supplement the adhesive. In accordance with the 45 method described in the aforesaid copending application, it is necessary to sever the upstanding elements 14 and 16 of the insole and the corresponding upstanding flange 33 of upper material flush with the bottom surfaces 30 and 32 throughout the forepart of the shoe to provide 50 a smooth, even bottom or foundation for the outsole. On the other hand, it is not necessary to trim these upstanding elements flush with the surfaces 30 and 32 in the shank portion of the shoe because the space between them will be 55 occupied by a shank-stiffener. Nevertheless, it is desirable to trim off some of the upstanding elements in the shank portion (see Fig. 4) to the end that their trimmed edges will be substantially flush with the bottom surface of the 60 shank-stiffener.

65 With regard to these requirements, the present invention provides an improved trimming machine by which, in one continuous operation beginning at the heel-seat portion of the shoe and progressing thence along one side of the shoe to and around the toe end and thence along the other side of the shoe to the heel-seat portion, the upstanding materials may be severed 70 above the staples 28 (see Fig. 4) at each side of the shank portion but severed flush with the surfaces 30 and 32 throughout the forepart.

75 The general organization of the illustrated trimming machine is similar to that of the machine illustrated in U. S. Letters Patent No.

429,065, granted May 27, 1890 on application of Schaadt and Clark, but the machine herein illustrated embodies certain novel features hereinafter described by which the closeness of trimming may be regulated by the operator while the trimming operation is in progress.

80 Referring to Figs. 1 and 2, the trimming means comprises two cutters or blades 36 and 38 which cooperate with successive shearing cuts against opposite faces of the material. The cutter 36 is affixed to the frame 40 by clamping bolts 42 and is provided with a vertical slot through which the shanks of these bolts extend, the slot providing for vertical adjustment of the cutter to insure a true shearing action. The cutter 38 is 85 carried by a horizontally movable slide 44 to which it is affixed by a clamping bolt 46. The slide 44 is arranged in a guideway formed in the frame 40 and is operated by an eccentric 48 to which it is connected by an eccentric strap 50, a pivot pin 52 forming the connection between the slide and the strap. The eccentric 48 is carried by a shaft 54 journaled in bearings in the frame 40 and provided with a receiving pulley over which a driving belt 56 runs. This receiving pulley is concealed in Fig. 1 by a hand-wheel 58 that appears in the foreground.

90 Referring to Fig. 2, the cutter 36 is provided with a shearing edge 60 that cuts against the inner face of the upstanding insole lip 16, and the cutter 38 is provided with a shearing edge 62 that cuts against the outer face of the upstanding flange 33 of upper material. These 95 edges remain always in lapped relation but are inclined in opposite directions with respect to the direction of feeding movement of the work which is indicated by an arrow in Fig. 2. The movable cutter 38, which is thin and flat, projects under the cutting edge of the stationary cutter 36. Consequently, when a shoe is presented to the 100 trimming means, as shown in Fig. 2, the surface 30 of the overdrawn portion of the upper will lie against the under surface of the blade 38 and thereby determine the level at which the work must be held to obtain flush trimming of 105 the upstanding elements on the shoe bottom.

110 A vertically movable trimming gage 64 is arranged to engage the bottom of the insole at a point in advance of the cutters with regard to the direction of feeding movement. Otherwise 115 stated, the work-engaging portion of the gage is at the feeding-in side of the trimming locality, and since it does not mask either of the cutters it may be raised sufficiently to provide for flush 120 trimming of the surplus materials by the cutters. This gage is arranged in a guideway or groove formed in the frame 40 and is maintained therein by a plate 66. The lower end of the gage projects laterally toward the movable blade 38 and is 125 preferably curved so that it may abut the insole only in the angle formed by the root 18 of the lip 16 and the channel from which the lip projects. Moreover, this laterally projecting extremity of the gage is preferably thin to clear the staples as 130 illustrated in Fig. 1. The lateral projection of the work-engaging extremity of the gage insures the described engagement with the root of the lip 16 even though the upstanding material on the insole may lean toward the middle of the shoe-bottom. However, even if the upstanding material does lean, the vertical portion of the gage will 135 clear it and thus avoid obstructing the feeding movement of the shoe.

140 Treadle mechanism is provided for moving the gage 64 up and down while the trimming opera- 145

tion is in progress, to the end that the gage may be used to depress the shoe and thereby cause the trimming means to sever the upstanding materials above the level of the staples 28, with the result shown in Fig. 4. For this purpose the frame 40 is provided with a lever 70, the fulcrum of which is indicated at 72. The forward end of the lever, which is forked, straddles a stud 74 carried by and projecting from the upper end of the gage 64. A rod 74 connected to the lever 70 by a pivot 78 extends downwardly through a boss 80 formed on the frame 40, the lower end of the rod being connected to a treadle 82 by a pivot pin 84. These elements are all normally raised by a tension spring 86, the ends of which are connected respectively to the treadle 82 and to an anchoring member 88 affixed to a supporting column 90 on which the frame 40 is mounted and to which the treadle is connected by a fulcrum pin 92. The rod 76 is provided with two adjustable collars 94 and 96 arranged respectively above and below the boss 80. These collars are provided with set-screws 98 by which they may be secured to the rod 76 at the desired positions to be arrested by the boss 80 and thereby establish the desired limits of vertical movement of the trimming gage 64.

In practice, the collar 96 will be secured to the rod 76 at a point that will permit the lower end of the trimming gage 64 to rise approximately to the level of the trimming cut, while the collar 94 will be set at a position that will enable the trimming gage to depress the shoe far enough to insure trimming the upstanding materials on the shoe bottom above the level of the staples 28.

In using the machine, the operator will present a shoe to the trimming means while holding the heel end of the shoe in the left hand and the toe end in the right hand and will begin the trimming operation near the heel end and feed the shoe from right to left (see the arrow in Fig. 2). At the outset, the operator depresses the treadle 82, thereby causing the trimming gage 64 to depress the shoe so that the upstanding materials on the shoe bottom will be trimmed above the level of the staples 28, as shown in Fig. 4. This position of the trimming gage will be maintained while the trimming operation progresses along the shank portion of the shoe, but when the trimming has progressed to a point in the vicinity of the forward end of the shank portion, the operator will permit the treadle to rise under the influence of the spring 86, meanwhile continuing to feed the shoe without interrupting its progress. As the trimming gage rises, the operator will raise the shoe as far as the surface 30 and the lower cutting blade 38 will

permit, and will preferably tip the shoe slightly toward the rear to insure severing the upstanding materials flush with the surfaces 30 and 32 (see Figs. 2 and 3). Under these conditions the trimming cut will be below the staples 28 in the ball portion of the shoe and these staples will remain in the strip 100 of surplus material that is cut off.

The flush trimming will be continued to and around the toe end of the shoe which will now be turned end for end so that the operator will hold the heel end in his right hand and the toe end in his left hand. From the toe end he will continue the trimming along the opposite side of the shoe, again feeding the shoe from right to left. When the flush trimming has progressed to a point at or near the junction of the ball portion and the shank portion, the operator will again depress the treadle 82, whereupon the trimming gage 64 will depress the shoe far enough to place the staples 28 below the plane of the trimming cut. This position of the trimming gage will be maintained until the trimming is finished at or near the heel seat.

Having thus described my invention, what I claim as new and desire to secure by Letters Patent of the United States is:

1. A trimming machine comprising a trimming gage the work-engaging portion of which is formed and arranged to bear in a channel in the bottom surface of the insole of a lasted shoe, cutting means arranged to sever a lip or flange of material projecting from said channel with a cut that may be flush with the bottom surface of the insole, the entire work-engaging portion of the gage being arranged at the feeding-in side of the trimming locality, and manually operative means by which the trimming gage and the cutting means may be relatively shifted while in operation to alter the closeness of the trimming cut. 105

2. A trimming machine comprising a trimming gage the work-engaging portion of which is formed and arranged to bear in a channel in the bottom surface of the insole of a lasted shoe, cutting means arranged to sever a lip or flange of material projecting from said channel with a cut that may be flush with the bottom surface of the insole, the entire work-engaging portion of the gage being arranged at the feeding-in side of the trimming locality and formed to engage the root of said lip or flange but to clear the surplus material projecting therefrom, and manually operative means by which the trimming gage and the cutting means may be relatively shifted while in operation to alter the closeness of the trimming cut. 120

GEORGE GODDU.
